UNITED STATES PATENT OFFICE.

GEORGE M. BARRY, OF RIDGEFIELD, NEW JERSEY.

DESIGN FOR A RADIO LOUD-SPEAKER.

Application filed May 9, 1928. Serial No. 26,615. Term of patent 3½ years.

To all whom it may concern:

Be it known that I, GEORGE M. BARRY, a citizen of the United States, and a resident of Ridgefield, county of Bergen and State of New Jersey, have invented a new, original, and ornamental Design for a Radio Loud-Speaker, of which the following is a specification, reference being had to the accompanying drawing, forming part of this specification wherein

Fig. 1 in the drawing shows in perspective from the rear a radio loud speaker embody-

ing my design a portion only of the border ornamentation being shown, it being understood that the balance is a mere repeat;

Fig. 2 is a side elevational view of the loud speaker embodying my design.

I claim:

The ornamental design for a radio loud speaker, as shown.

In witness whereof I have hereunto signed my name.

GEORGE M. BARRY.
